UNITED STATES PATENT OFFICE.

ALEXANDER BOYNTON, OF SAN ANTONIO, TEXAS.

POLISHED-ROD ROTOR.

Application filed June 19, 1928. Serial No. 117,194.

This invention relates to polished rod rotors especially adapted for use in pumping wells and an important object is to provide simple means whereby the polished rod and the reciprocating mechanism connected thereto may be rotated slightly on the down strokes of the polished rod to uniformly distribute wear and thereby avoid the necessity of frequently interrupting pumping for the purpose of renewing worn parts, such as cups or a plunger, as the case may be, the working barrel, stuffing box and polished rod.

Another aim is to provide simple means whereby the rotor is prevented from twisting the rods to the breaking point should the cups or plunger stick.

A further and equally important object of the invention is to provide a polished rod rotor which may be expeditiously attached without the exercise of unusual skill and without substantially modifying the structure of the parts in use.

Another aim of the invention is to provide a polished rod rotor in which the actuating member may be completely detached from the actuated part of the invention which is mounted on the polished rod to permit of the pulling of the rods without entirely dismantling the device.

Other objects and advantages will be apparent during the course of the following description.

In the accompanying drawings forming a part of this application and in which like numerals are employed to designate like parts throughout the same,

Figure 1 is a perspective of the improved rotor applied above the beam;

Figure 2 is a perspective of the improved rotor applied below the beam;

Figure 3 is a vertical sectional view through the improved rotor;

Figure 4 is a horizontal sectional view taken on line 4—4 of Figure 3;

Figure 5 is a perspective of a modified form of invention applied above the beam;

Figure 6 is a perspective of the rotor shown in Figure 5 applied below the beam;

Figure 7 is a vertical sectional view through the rotor shown in Figures 5 and 6;

Figure 8 is a horizontal sectional view taken on line 8—8 of Figure 7.

Figure 9 is a group perspective illustrating a slight modification of the invention.

In the drawings, the numeral 10 designates a beam adapted for reciprocating a polished rod 11 and the usual pumping equipment connected thereto. Of course, a driving connection is established between the rocking beam 10 and the vertically movable rod 11 through the usual polished rod trunnion as shown in the drawings. At this point it is noted that the employment of this invention contemplates the loosening of the clamping screw 12 of the trunnion so that intermittent rotation may be imparted to the polished rod as will be described. However, the clamping screw 12 may engage the polished rod until the device has been mounted above the beam as shown in Figure 1 or below the beam as shown in Figure 2 to support the weight of the rods during the attachment of the device.

The body of the rotor is more or less tubular and is designated by the numeral 14 and is designed to be secured on the polished rod by set screws 15. The set screws are preferably positioned adjacent the ends of the body 14.

In carrying out the invention, an attaching member 17 is rotatably mounted on the intermediate portion of the body and consists of a pair of substantially semi-circular sections adapted to be connected by fastening bolts 18 as clearly shown in Figure 4. The attaching member or carriage is confined between upper and lower annular flanges 19 and 20, respectively, and is held against endwise movement on the body by said flanges. However, the upper flange 19 is really unnecessary as the member 17 rests by gravity on the shoulder 20 so that the dog 22 carried by the housing 24 of the shell is at all times in operative relation to an annular series of ratchet teeth 26 on the intermediate portion of the body.

Figure 3 clearly illustrates that the attaching member 17 consists of upper and lower spaced straps arranged on opposite sides of the ratchet teeth 26 and provided with grease cups 29 by means of which the device may be lubricated. However, the lubricators 29 may be dispensed with and the device occasionally lubricated with the aid of a can 105 of oil.

Referring now to Figure 3, it will be seen that the dog 22 is movably positioned within the housing 24 and is urged into constant engagement with the teeth 26 by a coil spring 32 confined between the rear end of the dog and the inner end of a nut 33 which is threaded on the reduced terminal portion of the housing. The dog 22 is provided with a rearwardly projecting shank 34 which extends 10 radially and is surrounded by the convolutions of the spring 32. It will be seen that it is a simple matter to attach the dog to the housing as the removal of the nut 33 permits of the original introduction of the dog 22 and the spring and when the nut 33 is in place it will act as an abutment for one end of the spring and as a means to hold a combined bearing and swivel member 36 on the housing 24.

20 The member 36 is in the nature of an annulus mounted on the housing 24 between the nut 33 and an annular shoulder of the housing and the annulus is provided with radial lugs 40 to which the laterally slotted branches of an operating link 42 are connected. More specifically, the radial lugs of the combined bearing and swivel member 36 are received in laterally extending slots in the branches of the link 42 and permit the 25 link to partake of the limited swiveling movement about the axes of the lugs 40 when the rotor is in operation. In addition to this the mounting of the member 36 on the radial extension 24 permits the link 42 to partake of a limited movement about the axis of the radial extension in the operation of the improved rotor. It is thus seen that the housing 24 not only functions as such, but also as a trunnion for the connection of the operating link 42 to the dog carrying member.

30

40

The link 42 may be pivotally and adjustably connected to an actuator 46 as indicated at 47 and the actuator is provided with an attaching plate 48 which may be secured 45 to the beam by fastening bolts or other suitable means. It is here noted that the connection 47 may be quickly broken should it be desired to pull the rods, in which case the body 14 and associated elements may be 50 allowed to remain on the polished rod during the pulling operation. The actuator 46 is, of course, allowed to remain in place on the beam and will not in any way interfere 55 with the pulling of the rods.

55 In applying the improved rotor above the beam as shown in Figure 1 suitable washers may be mounted above the polished rod trunnion or a clamp 50 of conventional or other design may be positioned between the 60 polished rod trunnion and the lower end of the rotor. It is believed to be apparent that more rotating action may be obtained by elevating the body of the rotor by the employment of the clamp 50 or the equivalent thereof. A lubricating cup 51 and a washer

52 may be positioned directly beneath the body 14 and the cup employed for the reception of oil by means of which the contact surfaces of the washer 52 may be lubricated. This also gives greater elevation.

70 After the application of the washer 52 and the cup 51 the rotor may be slipped onto the polished rod and locked thereon as previously described.

Finally, the link 42 is connected to the member 36 and the actuator 46 and to adjust the rotor for proper operation the beam is positioned midway between the ends of its travel and the combined housing and trunnion 24 arranged at right angles thereto. The actuator 46 may have to be adjusted to some extent on the beam so the combined housing and trunnion 24 will be at exactly right angles to the beam when the beam is positioned midway of the ends of its travel. 80 This brings about the uniform movement of the rotor in both directions, but, of course, the polished rod is turned only on the descent of the reciprocating equipment.

85 By causing the turning of the rods on the descent thereof the load present on the up stroke of the rods is avoided and consequently the friction incident to the raising of the high column of fluid is avoided.

90 The intermittent rotation imparted to the rods during the rocking of the beam results in the uniform distribution of the wear which takes place on the cups, the working barrel, the stuffing box, and the like, and at the same time has a tightening effect on the rods so that parting of the rods and the 95 fishing jobs incident thereto are avoided.

100 When the rotor is applied below the beam as shown in Figure 2 the actuator 46 is, of course, positioned on the opposite side of the beam from where it was when the rotor was operating above the beam to bring about the intermittent rotation of the rods in the proper direction.

105 In the form of invention shown in Figures 5 to 8, inclusive, the structure is substantially the same as that illustrated in Figures 1 to 4, inclusive, except that the shank 122 of the dog is provided with an extension 124 which extends out through the outer end of the nut so that the same may be gripped by a pair of pliers or the like when it is desired to either apply or detach the member 117 mounted on the body 110 of the rotor. In this case the member 117 is in the nature of a band or annulus which extends about the body and is rotatably mounted upon the annular flange 120 as clearly shown in Figure 7. Figure 8 illustrates that the annulus 117 in this form 115 of invention may be cast in one piece and encloses the gear teeth with which the dog 120 is engaged.

125 This form of invention may operate above the beam as shown in Figure 5 or below

the beam as shown in Figure 6 and in either case will impart the desired intermittent rotation to the rods.

Particular attention is directed to Figures 5 1 and 2 which illustrate that the actuator 46 cannot be applied to the wrong side of the beam. This is true whether the actuator is applied for operating a rotor positioned above or below the beam. It will be seen 10 that since the actuator 46 extends out from one side of the attaching bar 48 the actuator may be positioned only on one side of the beam when it is desired to operate the rotor above the beam and on the opposite 15 side when it is desired to connect the same to a rotor below the beam. In other words, it is impossible to apply the actuator as designed to the wrong side of the beam. This is an especially important feature since 20 those who are charged with the care of the wells and the equipment are not always as careful as they might be.

As pointed out in the objects, the rotor cannot twist the rods to the breaking point 25 should the cups or the plunger stick. In explaining this, it is pointed out that each time the rotor turns the rods in a clockwise direction the rods will remain so turned by reason of the friction between the rotor body 20 14 and the washer 52 upon which the same is mounted. During the normal operation of the rotor there will be nothing of consequence to resist the intermittent turning of the rods and consequently the rods will remain in the position they are turned until 35 they are further rotated.

However, should the cups or the plunger stick, the rotor will continue to turn the rods until a back twist or strain is built up. 40 This back strain or twist, will of course, be in a counter clockwise direction. Considering Figures 1 and 3, it will be seen that when the back twist in the rods exceeds a predetermined point as a result of sticking 45 of the cups and the continued operation of the rotor the rotor body 14 will turn back in a counter clockwise direction each time the radial housing 24 and the actuator arm or link 42 is moved back. This prevents 50 the building up of additional back strain in the rods. It will, therefore, be seen that when the back strain exceeds a predetermined point the friction between the rotor body 14 and the washer 52 will be overcome 55 and the rotor body 14 will be moved back each time the housing 24 partakes of a counter clockwise direction so that the back twist in the rods is prevented from approaching the breaking point.

60 In the form of invention illustrated, in Figure 9 the radial housing is provided with a reduced terminal portion 160 upon which the semi-circular sections 161 of a swivel member corresponding to the swivel 65 member 36 are mounted. The semi-circular

sections 161 and the radial lugs 162 constitute an attaching means by which the forked terminal of the actuator 42 may be connected to the radial housing for operating the same. Of course a nut 163 may be employed 70 to hold the sections 161 in place.

Having thus described the invention, what is claimed is:

1. A polished rod rotor comprising a body adapted to be secured on a reciprocating portion of a well pumping equipment and being provided with teeth, a combined housing and trunnion having upper and lower straps rotatably connected to said body above and below said teeth, a dog within 80 said combined housing and trunnion and engaged with said teeth, a combined bearing and swivel rotatably mounted on said combined housing and trunnion, and an operating member swiveled to said combined bearing and swivel. 85

2. A polished rod rotor comprising a body adapted to be secured on a reciprocating portion of a well pumping equipment and being provided with teeth, a combined housing and trunnion having straps rotatably connected to said body at opposite sides of 90 said teeth, a dog within said combined housing and trunnion and engaged with said teeth, a combined bearing and swivel mounted on said combined housing and trunnion, an operating member swiveled to said combined bearing and swivel, and an actuator 95 connected to said operating member.

3. A polished rod rotor comprising a body adapted to be secured on the reciprocating equipment of a pumping well and being provided with ratchet teeth, a combined housing and trunnion member having upper and lower attaching straps secured to said body above and below said ratchet teeth, a dog within 100 said housing and adapted to engage said ratchet teeth, a spring within said housing and urging said dog into engagement with said teeth, a nut threaded on said combined housing and trunnion and constituting an abutment for one end of said spring, a combined bearing member and swivel rotatably mounted on said combined housing and trunnion, said nut being engaged with 105 said combined bearing and swivel to hold the same in place, and a link swiveled to said combined bearing and swivel. 110

4. A polished rod rotor comprising a body adapted to be secured on the reciprocating equipment of a pumping well and being provided with an annular series of ratchet teeth, a combined housing and trunnion member having attaching straps secured to 120 said body, a dog within said housing and adapted to engage said ratchet teeth, a nut threaded on said combined housing and trunnion and constituting an abutment for one end of said spring, a combined bearing 125 member and swivel rotatably mounted on said combined bearing and swivel mounted on 130

said combined housing and trunnion, said nut being engaged with said combined bearing and swivel to hold the same in place, a link swiveled to said combined bearing and swivel, and an actuator connected to said link and having means whereby the same may be connected to a beam.

5. In a polished rod rotor, the combination of an actuating member having a radial housing provided with a reduced terminal, a sectional swivel member mounted on said reduced terminal and having radial lugs,

and means to hold the sectional swivel member in place.

6. In a polished rod rotor, the combination of an actuating member having a radial housing, a swivel member rotatably mounted on said housing and consisting of separate sections, and an operating device having a forked terminal engaging the separate sections of said swivel member and having means holding the same in place. 15 20

In testimony whereof I affix my signature.
ALEXANDER BOYNTON.
